HAIR DRYER CASING

Leon F. Willat, Mill Valley, Calif.
(1077 Howard St., San Francisco 3, Calif.)

Filed May 17, 1965, Ser. No. 85,320

Term of patent 14 years

(Cl. D86—10)

FIG. 1 is a perspective view of a hair dryer casing, showing my new design.

FIG. 2 is a front elevational view thereof on a reduced scale,

FIG. 3 is a side elevational view thereof, and

FIG. 4 is a plan view thereof.

The characteristic feature of my design resides primarily in the rectangular, elongated, upstanding, arcuate tube member on the top of the casing body, which tube member essentially coincides with the taper of said casing body, all as shown.

I claim:

The ornamental design for a hair dryer casing, as shown and described.
